 Claims priority, application France Sept. 26, 1958
 9 Claims. (Cl. 158—131)

The present invention relates to a safety device for radiation burners or other similar heating appliances.

It is known that radiation burners are generally utilised for heating rooms and premises without being coupled to a smoke conduit enabling the gases of combustion to be evacuated to the exterior.

It is therefore necessary to provide such appliances with a safety device which puts them out of operation as soon as the proportion of CO₂ in the ambient air of the room exceeds a certain value, in order to ensure the safety of its occupants.

Certain types of safety devices are already known which comprise a by-pass or control burner nozzle in which a flame is maintained for heating a thermo-couple, the current of which ensures the operation of an electro-magnetic valve which in turn controls the supply of fuel to the appliance.

It is known that the speed at which the flame extinguishes increases when the quantity of CO₂ contained in the combustion-supporting air increases. As soon as the maximum proportion of CO₂ in the ambient air is reached, the flame is extinguished and, since the thermo-couple is no longer heated, the electro-magnetic valve is no longer excited and returns to its closed position.

The present invention has for its object to provide improvements for this type of safety device, enabling its sensitivity to be considerably increased.

This object is accomplished according to the present invention by the provision of a radiation burner in which the by-pass or control burner which heats the thermo-couple or other heat sensitive element is disposed to the rear of the face or flame surface of the radiation plate of the burner, which plate is provided with an orifice extending through it and opening approximately at its face so that when a fuel mixture is being burned at its face a draft of ambient air flows through the orifice toward the flame surface, and the control burner has a nozzle so disposed relative to the orifice that a flame issuing from the nozzle will be located within and cooled and otherwise influenced by the draft passing through the orifice, in a manner rendering the control burner flame highly sensitive to the presence of CO₂ in the draft.

According to another provision of the invention, the sensitivity of the control burner flame is further increased by tapering the extremity of the control burner nozzle so as to reduce the adherence of the flame to the nozzle.

According to another provision of the invention, the nozzle of the control burner is so disposed relative to the orifice extending through the radiation plate that the flame issuing from the nozzle is disposed within the orifice and, when the plate is disposed in upright working position, is inclined upwardly toward the face of the plate and extends in the direction of the flow of the draft passing through the orifice.

The thermo-couple is located in a position tangential with respect to the path of the by-pass flame, in such manner as not to intercept said flame nor to hinder its extinguishing.

The safety device is constructed in the form of a single-unit assembly which reduces the risk of leakage of gas, said assembly being carried by the mixer or injector chamber forming part of the equipped radiation burner.

2

The armature plate of the control lever of the regulator valve is coated with a layer of copper formed by electro-deposition, so as to avoid any adhesion to the cores of the electro-magnet due to residual magnetism.

5 One form of construction of the safety device carried out in accordance with the invention is described below, by way of example only and not in any sense by way of implied limitation, reference being made to the accompanying drawings in which:

10 FIG. 1 shows the safety device mounted on a radiation burner as seen from the rear of this latter;

FIG. 2 is a view of the same device looking on the front of the burner;

15 FIG. 3 is a cross-section taken along the line III—III of FIG. 1; and

FIG. 4 is a fragmentary cross-sectional view of the by-pass control nozzle showing the tapered extremity thereof.

In the form of construction of the device as shown, the said device is constituted by a regulator valve 1 provided with a coupling 2 intended to receive the fuel supply pipe and an outlet coupling 3 into which is screwed the main injector 4 of the mixer chamber 5 of the radiation burner 6. A swan-neck tube 7 is connected to the coupling 3 and terminates in a three-part coupling 8, the 20 moving member of which is coupled to an elbowed tube 9, the free tapered end of which forms a by-pass nozzle which is inclined upwards.

A calibrated injector 10 is screwed into the coupling 8, thus enabling the flow of gas fed through the by-pass 30 to be regulated, while the primary air of the by-pass reaches the coupling 8 through at least one hole 11 also calibrated and bored in the said coupling.

The whole assembly is mounted on the casing 6 of the radiation burner by means of a stirrup member 12 rigidly 35 fixed to the mixer chamber 5 which passes into the body of the burner.

The regulator valve 1 is operated by a lever 13 provided with a push-plate 14 enabling said lever to be actuated, which push-plate carries a plate 15 forming an armature designed to be retained by an electro-magnet 16 carried by a small plate 17 fixed to the body of the valve 1.

The coil windings of the electro-magnet 16 are constituted by a conductor, the two extremities 20a, 20b of 45 which are respectively coupled to the two elements 21a and 21b of a thermo-couple fixed on the by-pass 9 by means of a collar 22 in such manner as to be located in a tangential position with respect to the path of the by-pass flame. This position of the thermo-couple prevents 50 any interception of said flame and does not hinder its extinguishing action, as will be explained below.

The by-pass nozzle 9 is housed in a tubular conduit or sleeve member 23 passing through the gas chamber 24 of the appliance, and has its outlet at the rear of an orifice 55 formed in the radiation plate 26. A grid 27 forming a protective screen is mounted in front of the plate 26 in the usual manner.

The operation of the safety device is as follows:

When the gas (for example butane gas) arrives at a 60 certain pressure at the inlet 2 of the regulator valve 1, the disc 14 of the lever 13 is pushed down in order to open the regulator valve, which then reduces the pressure to a predetermined fixed value.

The gas thus expanded is then conveyed on the one 65 hand to the main injector 4 which feeds the burner 6 and, on the other hand, to the secondary injector 10 of the safety by-pass.

As soon as the by-pass and the burner are lighted, the thermo-couple is heated by a by-pass flame and generates a current which excites the electro-magnet 16. The latter retains the plate 15 of the lever 13 in contact with its cores, the plate 15 having previously been pressed against

the cores in order to open the valve 1 and to light the burner. In this way the valve is held in its open position by the electro-magnet.

A slight draught of air is thus produced through the conduit 23 and the orifice 25, caused both by the by-pass or control flame on the one hand and the radiation burner on the other. This slight current of air passes from the rear part of the burner towards the front of the appliance and surrounds the by-pass nozzle. Together with the gaseous mixture which reaches the by-pass nozzle, this air current assists in cooling the base of the flame of said by-pass in the centre of a burner which is considerably hotter than the by-pass.

In addition, the tapered extremity of the nozzle restricts the path and increases the velocity of the peripheral layer of the gas stream flowing through the nozzle, thereby creating in that layer beyond the nozzle orifice a velocity nearer to that of the core of the stream and rendering the control flame less stable than would be the case were the nozzle extremity untapered. The tapered extremity of the nozzle thus assists the extinction of the flame and, for these various reasons, the sensitivity of the device is substantially greater than that afforded by the devices already in existence.

It will be appreciated that if the proportion of CO_2 in the ambient air increases, this air charged with CO_2 constitutes the combustion-supporting air of the flame, and since the speed of extinction increases as the proportion of CO_2 increases, the flame will be extinguished as soon as this proportion exceeds a limit previously determined by suitable calibration of the by-pass injector and by appropriate dimensioning of the elements which either constitute or fix the by-pass in position.

The tapered extremity of the by-pass nozzle plays a very important part. In the first place, it eliminates any risk of backfire of the flame, and in the second place, were it not for this feature, the flame would be extinguished at 1% of CO_2 or more, whereas it has been observed in tests carried out with a tapered nozzle, that extinction takes place at less than 0.4% of CO_2 without hindering the ignition. The tapered portion thus makes the device much more sensitive to the presence of CO_2 .

It should also be noted that it is very important to place the by-pass in the bottom part of the appliance. In this position, a natural draught is set up between the grid and the radiation plate and also at the same time through the orifice 25, and it is this draught which ensures the correct operation of the device.

If the by-pass were placed near the top of the appliance, the orifice 25 would not contribute to the above-mentioned natural draught and would be liable to have the contrary effect of permitting the passage of reverse-currents of hot burnt gases which would heat the nozzle of the by-pass, causing the flame of the by-pass to backfire and thus making it more difficult to extinguish.

It is clear that as soon as the by-pass flame is blown out, the thermo-couple is no longer heated and ceases to generate a current capable of exciting the electro-magnet 16. The latter thus releases the plate 15 and the lever 13 returns to its position of rest, thus causing the valve 1 to close and cutting off the supply of fuel both to the burner and to the by-pass. The burner is extinguished and there is no longer any danger.

It is an advantage to coat the plate 15 with a film of non-magnetic material which is capable of preventing any untimely adhesion due to residual magnetism. The plate may be coated with a metallic layer, for example, copper, obtained by an electrolytic deposit of 3.5 microns in thickness. It may also be coated with a film of paint which is either applied by spreading or sprayed with a gun, or alternatively it may be coated with a non-magnetic film obtained by metallization.

In addition, the position of the by-pass nozzle with respect to the plate 26 should obviously be adjusted in a precise manner.

It is preferable to construct the device in the form of a single-unit assembly, in order to reduce the risk of leakages.

Finally, it will be understood that the form of construction described above, by way of example only and not in any sense by way of limitation, may be modified both as to form and detail, without thereby departing from the spirit or from the scope of the invention.

What I claim is:

1. A safety device for a radiation burner comprising: a radiation plate having perforations therein for conducting therethrough streams of a gaseous fuel mixture to be burned at the face of said plate, said plate further having an enlarged orifice extending through it and opening approximately at its face so that when a fuel mixture is being burned at its face a draft of ambient air flows through the orifice toward the flame surface; a main injector for supplying said mixture to said perforations; control burner means including a nozzle and an injector for supplying a stream of said mixture to said nozzle, said nozzle being disposed to the rear of the face of said plate in a position relative to said orifice such that a flame issuing from the nozzle will be located within and cooled to a temperature near its extinction temperature by the draft passing through the orifice; supply means including a valve effective when open to supply said mixture both to said main injector and to the injector of said control burner means; said control burner means and said supply means being operative to maintain said flame in a condition such that it will continue to burn when said draft contains no deleterious quantity of CO_2 but will be extinguished upon the occurrence of a deleterious amount of CO_2 in said draft; and control means, including a heat sensitive element in a position to be heated by said flame, for closing said valve when said element ceases to be heated by said flame.

2. A safety device as claimed in claim 1 wherein said orifice includes a sleeve member extending rearwardly from said plate and surrounding but spaced from said nozzle to funnel said draft of ambient air over said nozzle.

3. A safety device as claimed in claim 1 wherein said orifice is located near the bottom of said burner plate when said plate is disposed in upright working position.

4. A safety device as claimed in claim 1, said valve being normally closed, said control means including means movable to open said valve and means operative to hold said valve in open position as long as said element is heated by said flame.

5. A safety device as claimed in claim 1 wherein said nozzle has a tapered extremity so as to reduce adherence of said flame thereto and thereby facilitate extinction of said flame in the presence of CO_2 in the said ambient air.

6. A safety device as claimed in claim 1 wherein, when said radiation plate is disposed in upright working position, said nozzle forms within said orifice a flame angled upwardly toward said face of said plate and extending in the direction of the flow of said draft so as to facilitate extinction of said flame in the presence of CO_2 in the said ambient air.

7. A safety device for a radiation burner comprising: a radiation plate having perforations therein for conducting therethrough streams of a gaseous fuel mixture to be burned at the face of said plate, said plate further having an enlarged orifice extending through it and opening approximately at its face so that when a fuel mixture is being burned at its face a draft of ambient air flows through the orifice toward the flame surface; a main injector for supplying said mixture to said perforations; control burner means including a nozzle and an injector for supplying a stream of said mixture to said nozzle, said nozzle being disposed to the rear of the face of said plate in a position relative to said orifice such that a flame issuing from the nozzle will be located within and cooled to a temperature near its extinction temperature by the draft passing through the orifice; supply means

75

including a valve effective when open to supply said mixture both to said main injector and to the injector of said control burner means; said control burner means and said supply means being operative to maintain said flame in a condition such that it will continue to burn when said draft contains no deleterious quantity of CO₂ but will be extinguished upon the occurrence of a deleterious amount of CO₂ in said draft; and control means including a thermocouple in a position to be heated by said flame for closing said valve when said thermocouple ceases to be heated by said flame; said control means also including a valve lever having a displaced position whereat said valve is maintained in its open position, and an electromagnet responsive to current generated by said thermocouple while the thermocouple is heated by said flame to hold said lever in said displaced position. 15

8. A safety device as claimed in claim 7 wherein said thermocouple is located in a position tangential to the path of said flame.

9. A safety device for a gas burner comprising a 20 burner surface having a plurality of burner outlets and further having an enlarged orifice opening at said surface and extending rearwardly therefrom so that when a fuel mixture is being burned at said burner outlets a draft of ambient air flows through the orifice toward said surface; control burner means including a nozzle disposed to the 25 rear of said burner surface in a position relative to said

orifice such that a flame issuing from the nozzle will be located within and cooled to a temperature near its extinction temperature by the draft passing through the orifice; supply means including a valve effective when open to supply fuel both to said burner outlets and to said nozzle; said control burner means and said supply means being operative to maintain said flame in a condition such that it will continue to burn when said draft contains no deleterious quantity of CO₂ but will be extinguished upon the occurrence of a deleterious amount of CO₂ in said draft; and control means, including a heat sensitive element in a position to be heated by said flame, for closing said valve when said element ceases to be heated by said flame.
